UNITED STATES PATENT OFFICE.

WILLIAM H. HAYDEN, OF COLUMBUS, OHIO, ASSIGNOR TO THE P. HAYDEN SADDLERY HARDWARE COMPANY, OF SAME PLACE.

DESIGN FOR A HAME-HOOK.

SPECIFICATION forming part of Design No. 33,741, dated December 18, 1900.

Application filed November 19, 1900. Serial No. 37,068. Term of patent 14 years.

To all whom it may concern:

Be it known that I, WILLIAM H. HAYDEN, a citizen of the United States, residing at Columbus, in the county of Franklin and State 5 of Ohio, have invented and produced a new and original Design for Hame-Hooks, of which the following is a specification.

My invention relates to a new and original design for hame-hooks, and is illustrated in the accompanying drawings, in which—

Figure 1 is a front elevation, and Fig. 2 is a top plan view.

The leading features of my design reside in a hame-hook formed of a flat plate, one 15 end of which is deflected and extends backward toward the face of the plate and with its edge in contact therewith, forming a circular opening throughout the width of the plate, the face of the plate projecting from the side of this cylindrical end formation in a horizontal convex line, the opposite extremity of 20 said plate having a curved edge, said plate having formed in its face an opening, the stem of which leads in from the upper longitudinal edge of the plate, the walls of the latter defining said stem portion being plain 25 straight vertical walls, the base of the opening in the plate branching out in opposite directions from the stem portion and back again in a lower plane in parti-circular outlines, which terminate at points approximately directly beneath the said walls of the stem portion of the opening, leaving between said parti-circular openings a frusto-pyramidal formation, the top plane of which 30 frustum extends across beneath the stem portion of the opening and connects the terminations of the parti-circular openings.

In said drawings, the reference-numeral 1 indicates the hame-hook of my new and original design, the same being formed of a plate 2, one

end of which is deflected and extends backward toward the face of the plate, with its edge in contact therewith, as at 3, forming a circular opening 4 throughout the width of 45 the plate. The face of the plate projects from the side of this cylindrical end formation in a horizontal convex line, as shown. The opposite extremity of the plate is formed with a curved edge 5. Formed in the plate 50 is an opening, the stem 6 of which leads in from the upper longitudinal edge of the plate, said stem having straight sides defined by the plain or straight vertical walls 7 of the plate. The base of the opening in the plate 55 branches out in opposite directions from the stem portion and backward again in a lower plane in parti-circular outlines 8, which terminate at points approximately beneath the walls of the stem portion of the opening, 60 forming partly-circular openings 9 and leaving between the said partly-circular openings a frusto-pyramidal formation 10, the top plane 11 of the frustum extending across beneath the stem portion 6 of the opening and connecting the terminations of the parti-circular outlines 8.

My design presents a hame-hook having a novel, pleasing, and distinguished appearance.

Having thus described my design, what I claim is—

The design for a hame-hook herein shown and described.

In testimony whereof I have hereunto set 75 my hand in presence of two subscribing witnesses.

WILLIAM H. HAYDEN.
